UNITED STATES PATENT OFFICE

LOUISE R. PORTS, OF TROUTDALE, OREGON

MOVING DISPLAY SIGN

Application filed December 11, 1928. Serial No. 325,289.

My present application relates to my United States patent application, Serial Number 52,113, filed August 24, 1925, upon a Moving display sign.

5 The object and purpose of my present application is a simplified form of construction, adapted for use in the displaying of a multiplicity of signs continuously appearing in the same order within a relatively narrow 10 display case, the case being adapted to display a permanently fixed sign on either side and at the lower edge thereof, means being provided within the end structure to indicate in moving form a disappearing sign that 15 disappears and reappears in timed relationship.

A further object of my present invention consists in a sign relatively cheap in manufacturing cost, one adapted for the advertising of a relatively large number of products, 20 and one that can be safely hung and maintained in an open passageway or over a sidewalk.

Still further objects of my present invention consist in a device that may be operated over relatively long periods without attention or care.

A still further object of my invention consists in providing means whereby the direct 30 rays of lights will fall directly upon the movable sign boards during a part of their travel and expose them to view and during the rest of their travel will remain in shadow.

And still further objects of my invention 35 consist in providing a base adapted to prevent the falling of one or more of the sign elements should the same become disconnected.

With these and incidental objects in view, 40 the invention consists in certain novel features of construction and combination of parts, the essential elements of which are set forth in the appended claims, and a preferred form of embodiment of which is hereinafter shown with reference to the drawings 45 which accompany and form a part of this specification:

In the drawings:

Fig. 1 is a side elevation of the assembled 50 device.

Fig. 2 is an end view, taken on line 2—2 of Fig. 1, looking in the direction indicated.

Fig. 3 is a longitudinal, cross section view, taken on line 3—3 of Fig. 4, looking in the direction indicated.

Fig. 4 is a cross sectional front view taken 55 on line 4—4 of Fig. 2, looking in the direction indicated.

Fig. 5 is a sectional, end view, taken on 60 line 5—5 of Fig. 4, looking in the direction indicated.

Fig. 6 is another embodiment of the end view taken on line 2—2 of Fig. 1, looking in the direction indicated.

Like reference characters refer to like 65 parts throughout the several views.

I preferably form my display case of a rectangular housing, having paneled side walls 1, and 2, the same being adapted for the placing thereupon of a relatively permanent sign on which the main products to be advertised are displayed at either side of the display case. A top wall 3, connects the sides and ends. The ends are shown at 4 and 5. The end structures have supporting 70 bases for the brackets and journals to be secured thereto upon which the sign structure is mounted.

Oppositely disposed brackets 6 and 7 are 75 mounted within the case within which journal shafts 8 and 9 are mounted. The journal shafts are preferably made in the form of stub shafts to which are mounted toothed sprocket wheels 10. Disposed in the lower part of the case or jacket is a transverse shaft 11, journaled within suitable journals 12 and 13. Also secured to the shaft 11 are toothed sprockets 13. The shaft 11 is the driving 80 shaft and the sprockets 13 are fixedly secured thereto. Endless chains 14 and 15 are

trained about the sprockets and are driven 85 in timed relationship with each other. A prime mover, as an electric motor 16, is mounted within the case and has a worm reduction gear 17, secured to the main driving shaft which is adapted to coact with the worm wheel 18, also fixedly secured to the shaft 11. This imparts rotation to the shaft 11 and to the sprockets 13, mounted thereupon, and likewise to the endless driver ele- 90

95

100

ments 14 and 15. The sprockets mounted adjacent either end of the shaft 11 are alike in diameter and number of teeth so that the elements being driven thereby are driven also in timed relationship. The lower surface 19 of the case is cut away, as shown at 20, to permit of the sprockets and chain extending therebelow, and secured to the chains are a multiplicity of sign boards 21. Each of the sign boards have an outwardly extending supporting lug 22, disposed at either end thereof which acts as a journal for the supporting pin 23, directly positioned upon the chain. Each of the sign board elements 21 is adapted and arranged for having a sign placed on oppositely disposed sides of the board so that when the same appears below the bottom of the case, the same may be readily observed from either side. The mechanism, as herein illustrated, has arranged thereupon signs as would be used in conjunction with a bath house or a manufacturer of bathing suits and the like, and in order to further carry out this line of advertising, I have illustrated upon the end section 5 of the case, a panel in which is portrayed a bath pool or pond 24, and I place upon the stub shaft 9, a disk or disk segments 25 which are adapted for rotation with the rotation of the shaft 9, and I display upon the segment 25 one or more figures 26, here portrayed as a diving nymph, so that but one of the figures appear at a time and the disappearing of the same behind the pool, leaves the impression with the observer that the nymph is diving into the pool. The same may be portrayed upon a disk 27, as illustrated in Fig. 5, and as the same is rotated the diving nymph will appear to plunge into the pool.

My invention is primarily intended for use in towns, villages and cities wherein density of traffic is to be considered, and wherein signs are placed and maintained under ordinances, and operated by license. In many of the cities ordinances prohibit the hanging or maintaining of signs over sidewalks, where moving parts are in operation without safety devices being placed adapted to prevent the falling or dropping of the moving elements should the same become disengaged or disconnected from its supporting element. I place supporting elements 28 adjacent each corner of the case structure and extend the same downwardly for a sufficient distance to permit the cross bars 29 and the screen bottom 30 to clear the signboard 21, when at its lowest point. In the event of the signboard element becoming disengaged from the endless chain elements, the same cannot drop to the street but will be maintained upon the supporting element 30. I preferably form the supporting element 30 of a relatively coarse screen or lattice work sufficiently strong to support the signboard, and suffi-

ciently open in its construction to permit of the passage of the light therethrough.

It is highly desirable to illuminate the signboards as the same come into view and to intensify the light for a limited time only as the signboard comes into view and to prevent the strong rays of the light being directed upon the signboard for the full passage of the same to view. Best results being obtained wherein a light 31 is placed below the sign on the side where the sign board travels toward the light and by placing a light 32 above the signboard where the signboard travels away from the light. By so placing the lights for the signboards, best results obtain and the signboards will be illuminated to the best advantage for the advertiser. Each of the lights should be so placed as to be out of vision from the reader of the signs.

Where the bathing nymph 26 is desired to appear as if diving from a spring board, the same may be accomplished as shown in Fig. 6, wherein the spring board is shown at 33 and the nymph 34 is attached to an arm 35 directly attached to the driving shaft. The nymph appears immediately above the spring board and is secured to the outer end of the arm 35 similar in color to the field of the scene and thus appears to be unattached and will in appearance dive into the water as illustrated.

I do not wish to be limited to a diving figure, as the same is susceptible of portraying any number, or variety of objects of which this is intended as a single example.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination of a case, display panels disposed in oppositely disposed sides of the case, endless chains disposed about supporting elements disposed within oppositely disposed ends of the case, a driving element for the chains, a multiple of display sign boards hingedly mounted upon the endless chains and adapted for displaying below the bottom edge of the case in continuous display as the chains are rotated about the supporting elements and a disk secured to one of the upper stub shafts disposed at the outer end of the display case and a display disposed upon the disk and said display disposed so as to appear and disappear as the disk is rotated.

2. In a device of the class described, the combination of a display case, display pan-

els disposed on the outer surfaces of the case, shafts and supporting journals disposed within the case, sprockets in registerable alignment disposed within each end of the case, supporting elements trained about the sprockets, a prime mover for imparting movement to the supporting elements, simultaneously, display signboards disposed in spaced relationship upon the supporting elements, and a disk mounted on the outer end of one of the upper sprockets having one or more images disposed upon the outer surface thereof.

3. In a device of the class described, the combination of a display case, display panels disposed on the outer surfaces of the case, shafts and supporting journals disposed within the case, sets of sprockets disposed upon the shafts in registerable alignment, endless supporting elements trained about each set of sprockets, means for driving each set of sprockets and the elements trained thereabout in timed relation with the other sets of sprockets and the endless supporting elements, a prime mover for imparting movement to the endless supporting elements, a multiple of signboards disposed in spaced relationship hingedly secured to the endless supporting elements, illuminating elements disposed within the base and a screen base adapted for supporting disengaged signboards disposed across the bottom of the case and spaced therefrom.

4. In a device of the class described, the combination of a display case, display panels disposed on the outer surface of the case, endless supporting elements disposed at the inner ends of the case, power means for driving each of the endless supporting elements in timed relation with each other, signboards hingedly supported by the endless supporting elements in spaced relation thereupon, means for illuminating each of the signboards for a part of its travel at either side and means for maintaining disengaged signboards within the base of the case.

LOUISE R. PORTS.
